UNITED STATES PATENT OFFICE.

GEORGE H. BARTLETT, OF SAN FRANCISCO, CALIFORNIA, ASSIGNOR TO NATIONAL PAPER PRODUCTS CO., OF SAN FRANCISCO, CALIFORNIA, A CORPORATION OF CALIFORNIA.

CORRUGATED-PAPER TUBE.

1,319,455.

Specification of Letters Patent. Patented Oct. 21, 1919.

Application filed February 14, 1918. Serial No. 217,062.

To all whom it may concern:

Be it known that I, GEORGE H. BARTLETT, a citizen of the United States, residing at the city and county of San Francisco and State of California, have invented new and useful Improvements in Corrugated - Paper Tubes, of which the following is a specification.

This invention relates to a paper tube and the process of making same.

It is the principal object of this invention to provide a paper tube which may be rapidly manufactured and which is so formed as to possess considerable strength as well as to provide an interior lining which will protect fragile objects inclosed therein.

The present invention contemplates the use of flat cardboard sheets wrapped helically upon a paper tube forming machine of common construction and which are combined in the course of manufacture with layers of helically arranged sheets of corrugated cardboard.

Certain forms into which the tubes are made and an embodiment of a machine for producing such tubes are illustrated by way of example in the accompanying drawings, in which—

Figure 1 is a view disclosing a length of tube formed according to the spirit of the present invention and with a portion of its outer wall broken away to indicate the joint in the wall layer therebeneath.

Fig. 2 is a view in transverse section, as seen on the line 2—2 of Fig. 1, illustrating the correlation of the outer solid wall and the inner corrugated wall combined therewith.

Fig. 3 is a view in transverse section illustrating the tubing as crushed to conserve space in shipping.

Fig. 4 is a fragmentary view illustrating the arrangement of the outer and inner thicknesses of the tube wall and the manner in which their joints are disposed.

Fig. 5 is a view in diagram disclosing one form of tube wrapping machine upon which the tubes may be made.

Fig. 6 is a view in transverse section, disclosing a second form of tube having an inner and outer thickness of cardboard and an interposed layer of corrugated material.

Referring more particularly to the draw-

ings, 10 indicates the cylindrical mandrel of a paper tube forming machine of common construction. Suitably mounted upon diametrically opposite sides of the mandrel and in a plane diagonal to the longitudinal axis thereof are multiple grooved pulleys 11 and 12 which carry a series of wrapping belts 13. These belts are carried one turn around the mandrel and are used to wrap strips of cardboard 14 and 15 thereon with the side edges of the coil in abutting relation.

As illustrated in Fig. 5, the cardboard 14 is smooth and flat while the cardboard 15 is corrugated. As arranged, the corrugated cardboard will be wrapped directly around the mandrel and the smooth cardboard wrapped thereover; the joints of the convolutions of each cardboard occurring intermediate the width of the other cardboard, as particularly shown in Fig. 4. While the belts are driven in the direction of arrows *a*, as shown in Fig. 5, the two-ply tube will be formed and the two layers of cardboard will be helically arranged. The layers are arranged in overlapping relation, the side edges of the smooth layer being located at the median plane of the corrugated layer and the corrugated layer having its side edges located at the median planes of the smooth layer.

As the wrapping continues the tube will be forced along the mandrel in the direction of arrow *b*, it being understood that a suitable adhesive material has been applied to the adjacent faces of the two cardboard layers so that they will adhere to form a tube having the cross section indicated in Fig. 2.

A tube of the character shown in Fig. 2 will have a helically wrapped outer wall of smooth cardboard and a helically wrapped inner wall of corrugated cardboard. It will be readily recognized that these two walls so arranged will have greater strength than two similar walls of smooth cardboard, due to the corrugations of the board and their helical arrangement and that a desirable cushion will be formed to protect fragile objects packed within the tube.

In order to conserve space in shipping the empty tubes a pair of crushing rollers 16 and 17 is spaced adjacent to the outer end of the mandrel 10 and equidistant from the longitudinal axis thereof. In this manner they

will provide a throat through which the tube will be forced. This will cause the rollers to crush the tube, as shown in Fig. 3, after which it may be cut in lengths by the revolu-
5 ble cutting member 18.

It will be readily recognized that paper tubing designed for different uses may be made by this machine and its strength readily determined. Fig. 6 discloses one
10 other form of the tube which is provided with an outer smooth cardboard layer 19, a smooth inner layer 20 and an intermediate layer of cardboard 21, all of which are helically wrapped and are treated with an ad-
15hesive material to form a unitary wall structure. This form of tube will thus have smooth inner and outer walls and an intermediate stiffening and buffer wall. It is evi-
20 dient that other modifications of the inven-
tion could be readily produced as occasion demands.

It will thus be seen that when paper tubes are formed according to the spirit of the present invention their walls will be uni-
25 form in thickness and the smooth layers of the walls perfectly flat without creases and breaks as commonly occur when combining flat cardboard and corrugated paper to form circular containers. It will further be noted
30 that due to the fact that the corrugations extend helically the strength of the tube will be materially increased without adding to its weight, and thus strong protective tubes may be made of paper in a rapid and inex-
35 pensive manner not possible when made as commonly constructed.

While I have shown the preferred form of my invention as now known to me, it will be understood that various changes in the com-
40 bination, construction and arrangement of parts may be made without departing from the spirit of the invention as disclosed.

Having thus described my invention, what I claim and desire to secure by Letters Patent is—

1. A paper tube comprising alternate layers of smooth and corrugated paper helically wrapped in overlapped relation to each

other, each layer having the side edges of its convolutions in abutting relation.

50

2. A paper tube comprising an outer layer of smooth cardboard wrapped helically, and an inner layer of corrugated cardboard wrapped helically in overlapped relation with respect to the outer layer and glued to the said outer layer to form a composite wall, the side edges of the convolutions of each layer being in abutting relation.

55

3. A cardboard tube comprising layers of flat cardboard and layers of corrugated card-
60 board arranged helically and glued in overlapped relation to each other with the side edges of one of the layers at substantially the median line of the other layer.

4. A method of forming a cardboard tube, 65 consisting in simultaneously wrapping layers of smooth and corrugated cardboard in overlapped relation around a forming mandrel with the side edges of one layer at substantially the median line of the other layer and applying an adhesive material to their adjacent sides whereby a composite tube will be formed.

70

5. A method of forming corrugated card-
75 board tubes consisting in simultaneously wrapping layers of flat and corrugated card-
board upon a cylindrical mandrel and in superimposed overlapping relation to each other, applying an adhesive to the adjacent faces of the layers, and thereafter passing 80 the tube through a pair of crushing rolls after which it is severed into lengths.

6. A paper tube comprising layers of flat and corrugated cardboard helically wrapped in overlapping relation with the side edges 85 of the corrugated layer substantially at the median line of the smooth layer and with the corrugations extending spirally around the tube.

In testimony whereof I have hereunto set 90 my hand in the presence of two subscribing witnesses.

GEORGE H. BARTLETT.
